(57) **CLAIM**

The ornamental design for a candle wick trimmer, as shown and described.

DESCRIPTION

FIG. 1 is a front, right, and top perspective view of a candle wick trimmer, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the candle wick trimmer that form no part of the claimed design.
